GEORGE A. CROSMAN, OF SEATTLE, WASHINGTON

REMOTE-CONTROLLED DOOR-OPERATING MECHANISM

Application filed February 26, 1929. Serial No. 342,725.

This invention relates to devices for hanging and operating doors and, more especially, those of large size such as employed in automobile garages, warehouses, machine shops 5 and the like.

The object of the invention, generally, is to provide devices of this character which will be of inexpensive and durable construction, and efficient in operation.

10 A more specific object is to provide door suspending means adapted to cooperate with the door hinges to support heavy doors so that they cannot sag, and permitting the same to be readily swung in their opening and closing movements.

15 A further object is to provide conveniently actuated means remote from the door to effect movement thereto by utilizing the door supporting devices as parts of the door operating 20 appliances.

Other specific objects and advantages of the invention will appear in the following description.

25 The invention consists in the novel construction, adaptation and combination of parts hereinafter described and claimed.

In the accompanying drawings,—

Figure 1 is a front elevational view of a room wall provided with a doorway, a side 30 wall of the room in transverse section, and a pair of hinged doors equipped with an embodiment of my invention; Fig. 2 is a horizontal sectional view of Fig. 1; Fig. 3 is a fragmentary front elevation, partly in section through 3—3 of Fig. 4, illustrating to an 35 enlarged scale the application of the door braces, hangers, and carriage mounting as utilized with a sidewall track; Fig. 4 is a view partly in horizontal section and partly 40 in plan of parts shown in Fig. 3; Fig. 5 is a view in front elevation of the door operating means; and Fig. 6 is a perspective view of a carriage track and bracket assembly.

45 In Figs. 1 and 2, to which reference is now had, 10 and 11 represent a pair of doors for a doorway 12 in a front wall 13 of a building and adjacent to a side wall 14 thereof.

50 As shown, these doors are connected to the wall 13 at opposite sides respectively of the doorway by means of hinges 15 so as to be

swung as indicated by the dotted lines 16 in Fig. 2.

Each of said doors may be of a single member or, as shown in Fig. 1, of two complementary parts, the lower parts being denoted 55 by 10¹ and 11¹ which are adapted to be detachably connected to the associated upper parts as by means of latch bolts 17 or equivalent devices.

In carrying out the invention, I provide for 60 each door, supporting means therefor comprising two rods 18 and 19; the rod 18, hereinafter designated as the tie-rod, is disposed horizontally, or nearly so, and has one of its ends pivotally connected by a pin 181 for vertical adjustment to a coupling 182 which, in turn, is connected for horizontal swinging movement, by means of a pin 20, to an attachment 21 secured to the free side of the door. The other end of a tie-rod is pivotally 65 connected for vertical adjustment by means of a pin 183 to a winged connector 22 which, in turn, is connected for horizontal swinging movement by means of a pin 221 (Fig. 4) 70 to a block 23. The other above mentioned rod 19, hereinafter termed the suspension-rod, is pivotally connected by means of a pin 191 for vertical adjustment to said connector 22 and is thus horizontally in unison with the tie rod 18 for operating the door. The suspension rod 19 extends downwardly in angular relation with respect to the tie rod 18 and has its lower end pivotally connected for vertical adjustment to a coupling 192 (Fig. 1) which, in turn, is pivotally connected for 75 horizontal swinging movements by means of a pin 20¹ to an attachment 21¹ secured to the door, in spaced relation with the attachment 21.

With respect to the door 10 adjacent to a side wall, as 14, the block 23 is connected by means of a horizontally disposed swivel pin 24 with a carriage or trolley 27 mounted to move to and fro in a horizontal track 25 of known construction, preferably of the U-type, which is secured to the wall as by 80 means of brackets 26.

The block 23 for the companion door 11 has its trolley track 25¹ supported by means 85 of brackets 26¹, secured to the wall 13, such 100

track being disposed in offset angular relation to the wall substantially as represented in Figs. 2 and 6, so that the plane of the braces or rods, as indicated by 18¹ in Fig. 2, will occupy an angular relation with respect to the wall 13 when the referred to door occupies the closed position in which it is represented by full lines in Figs. 1 and 2.

In its illustrated embodiment the swivel pin 24¹ depends from the associated trolley 10 through a slot 252 (Fig. 6) in the bottom of the track 25¹. Each door is swung to open and close the same by means of a cable 28 wound intermediate its length 15 about a drum 29 (Fig. 5), which is fixedly secured to a spindle 30 rotatable in a frame 31 which is secured to the building wall, 13 or 14, remote from the respective door. A drum is actuated to operate the associated 20 door through the medium of a crank handle 32 fitting a polygonal end of the spindle.

Said cable, one for the trolley of each 25 door, has its ends 28¹, connected to the associated trolley as by means of a collar 33 mounted upon the respective swivel pin 24, or 24¹ and having apertured lugs to which said cable ends are secured.

From said trolley connections, the cable 30 passes about guide pulleys, as 34 and 35, and thence to the drum 29.

For securing a door in an adjusted position, I provide upon a drum spindle 30 a toothed wheel 36, Fig. 5, which is adapted to be engaged by a detent 37 controlled by 35 a finger 38 slidable in a slot 39 of the frame 31.

Operation.—A door is swung about its hinges by means of the respective cable 28 actuated by a proper turning of its drum 40 29 to cause the trolley for the door to be moved in one direction or the other upon the track therefor.

Movement of the trolley in either direction 45 is transmitted to the door through the medium of the stiff rod members 18, 19 of the door supporting frame. Such frame members moreover by being connected in spaced apart relation to the free side of a door constitute two sides of a triangle which obviously prevents any sag to the door.

Two-part doors are movable as a single piece when the parts thereof are coupled together by the releasable means 17.

What I claim is,—

1. In combination with a building structure and a door hingedly connected thereto, a track rigid with said structure at the hinged side of the door, a member arranged to travel on said track, rod devices operatively connecting said member with the free side of the door at different elevations, and means connected to said member to impart door opening and closing movements thereto.

2. In combination with a building structure and a door hingedly connected thereto,

a track rigid with said structure at the hinged side of the door, a trolley arranged to travel on said track, door suspending and operating rod devices connecting said trolley with the door, and means associated with said trolley to impart door opening and closing movements to said rod devices.

3. In combination with a building structure and a door hingedly connected thereto, a track rigidly secured to said structure, a trolley member arranged to travel to and fro upon the track, means including complementary rods connecting said door with the trolley member, means connected to said trolley member to impart door opening and closing movements to the rods, said rods being disposed one above the other, the lower of which rods being connected to the door at its free side to suspend the same against sagging.

4. In combination with a building structure and a door hingedly connected thereto, a member adapted to move to and fro, complementary rods connecting said door with said member, and means connected to said member to transmit door opening and closing movements to both of the rods, said rods being arranged one above the other, the lower of which rods being connected to the free side of the door to prevent the sagging of the same.

5. In combination with a building structure and a door hingedly connected thereto, a track secured to the structure in spaced relation with the wall thereof to which the door is hinged, a trolley mounted on the track, a block, a swivel pin connecting said block to the trolley, two rods disposed in relative angular relation one above the other and connecting said block to the door in proximity to the free side of the latter, the connections of the rods with the door and the block permitting vertical adjustment to the rods and horizontal swinging movement of the door, flexible connections with both ends of said trolley, and a manually operable drum disposed remote from the door for actuating said flexible connections to impart door closing and opening movements to the trolley and the rods.

6. In combination with a building structure and a door hingedly connected thereto, a track secured to the structure in spaced relation with the wall thereof to which the door is hinged, a trolley mounted on the track, a block, a swivel pin connecting said block to the trolley, two rods disposed in relative angular relation one above the other and connecting said block to the door in proximity to the free side of the latter, flexible connections with said trolley, and a rotary drum disposed remote from the door for actuating said flexible connections to impart door closing and opening movements to the trolley and the rods.

7. In combination with a building structure and a door hingedly connected thereto,

a track secured to the structure in spaced relation with the wall thereof to which the door is hinged, a trolley mounted on the track, a block, a swivel pin connecting said block to the trolley, two rods disposed in relative angular relation one above the other and connecting said block to the door in proximity to the free side of the latter, flexible connections for said trolley, a manually operable drum disposed remote from the door for actuating said flexible connections to impart door closing and opening movements to the trolley and the rods, and means for locking the drum to secure the door in a selected position.

15 8. In combination with a building structure and a door hingedly connected thereto, a track secured to the structure in spaced relation with a wall thereof, a trolley mounted to travel on the track, a block, a swivel pin connecting said block to the trolley, two rods disposed in relative angular relation one above the other and connecting said block to the door in proximity to the free side of the latter, the connections of said rods with the 20 block and the door permitting vertical adjustments of the rods and horizontal swinging movements to both the door and the rods flexible connections with said trolley, means for actuating said flexible connections to impart door closing and opening movements selectively to the trolley and the rods, and means for releasably securing the door in a 25 selected position.

9. In combination with a building structure and a door hingedly connected thereto, a track secured in rigid relationship with respect to said structure, a trolley arranged to travel on said track, operating devices connecting said trolley with the door, and means associated with said trolley to impart door 30 opening and closing movements to said operating devices.

Signed at Seattle, Washington, this 14th day of February, 1929.

45 GEORGE A. CROSMAN.
